(57) **CLAIM**

The ornamental design for a lawn fork, as shown and described.

DESCRIPTION

FIG. 1 is a perspective view of a lawn fork showing a first embodiment of our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view thereof, showing the status while in use;

FIG. 10 is a perspective view of a lawn fork showing a second embodiment of our new design;

FIG. 11 is another perspective view thereof;

FIG. 12 is a front view thereof;

FIG. 13 is a rear view thereof;

FIG. 14 is a left side view thereof;

FIG. 15 is a right side view thereof;

FIG. 16 is a top view thereof;

FIG. 17 is a bottom view thereof; and,

FIG. 18 is a perspective view thereof, showing the status while in use.

The dashed broken lines illustrate portions of the lawn fork that form no part of the claimed design. The dashed broken lines showing a handle in FIGS. 9 and 18 are for the purpose of illustrating environmental structure, and form no part of the claimed design.

1 Claim, 14 Drawing Sheets
